UNITED STATES PATENT OFFICE.

AMOS SAWYER, OF HILLSBOROUGH, ILLINOIS.

DESIGN FOR A TONGUE-DEPRESSOR.

SPECIFICATION forming part of Design No. 28,973, dated July 5, 1898.

Application filed April 18, 1898. Serial No. 678,084. Term of patent 7 years.

To all whom it may concern:

Be it known that I, AMOS SAWYER, a citizen of the United States, residing at Hillsborough, in the county of Montgomery and State of Illinois, have invented a new and original Design for a Tongue-Depressor, of which the following is a specification.

This invention relates to a new and original design for a tongue-depressor; and it has for its object to provide a design of this character that shall be both useful and ornamental.

The leading feature of the design resides in a tongue-depressor having a longitudinally straight blade of a concavo-convex shape in cross-section, with the concavity located at the upper side of the blade.

In the drawings, Figure 1 is a perspective view of a tongue-depressor embodying the herein-described design. Fig. 2 is a plan view 20 of the blade. Fig. 3 is a detail section on the line 3 3 of Fig. 2.

Referring to the drawings, the numeral 1 designates the straight handle of the depressor, having curved laterally therefrom at one end and at right angles thereto the blade 25 2. The blade 2 is longitudinally straight and flares in width toward its outer rounded end edge 3. The said blade 2 is of a concavo-convex shape in cross-section, and has the concavity thereof at its upper side. 30

What I claim is—

The design for a tongue-depressor, herein shown and described.

In testimony that I claim the foregoing as my own I have hereto affixed my signature in 35 the presence of two witnesses.

AMOS SAWYER.
